SHOE OR SIMILAR ARTICLE

Francis Xavier Lipare, New York, N. Y.

Application February 1, 1957, Serial No. 44,705

Term of patent 3½ years

(Cl. D7—7)

The figure on the drawing is a perspective view of a shoe or similar article, showing my new design. The opposite side of the shoe is substantially plain.

The dominant feature of my design resides in the portions shown in solid lines.

I claim:

The ornamental design for a shoe or similar article, substantially as shown and described.
